Letters Patent No. 88,994, dated April 13, 1869.

IMPROVEMENT IN STAIR-RODS.

The Schedule referred to in these Letters Patent and making part of the same.

To all whom it may concern:

Be it known that I, H. UHRY, of the city of New York, in the county and State of New York, have invented certain Improvements in Stair-Rods; and I do hereby declare that the following is a full and exact description thereof, reference being had to the accompanying drawings, in which—

Figure 1 represents a front view of the end of my improved stair-rod, as seen when the same is in place;

Figure 2 is a longitudinal horizontal section of the same, when made of metal;

Figure 3 is a like representation of the rod, when made of wood;

Figure 4 is a front view, as fig. 1, with the ring instead of the cap-fastening; and

Figure 5 is a horizontal section of fig. 4.

This invention relates to an improved fastening for stair-rods; and

It consists, in the combination with said rod, of an end-cap, or over-ring, sliding freely upon or over the rod, and a hook, T, whereby a secured and neat fastening is obtained, as hereafter specified.

A is a rod, which may be made of any shape or material, as taste or fancy may dictate.

B is the staircase, to which it is desired to attach the rod A.

C is a cap, or C' is a ring, both made of proper shape and size, to slip freely over the rod A; and

T is a hook, driven or screwed into the staircase, as indicated in the drawings.

The rod A, when made of wood, has a slotted hole, H or S, made at both of its ends, of proper dimensions to receive the hook T.

When the rod A is made of metal, only one slotted hole, K, is required, at one of its sides, but at both ends.

The ring C', or cap, C, has a small slotted hole, D, cut on one of its sides, so that the shank of the hook T may enter therein, and enable the ring C', or cap, C, to be slipped far enough to effectually conceal the slotted hole H or S, in the wooden rods A.

By this arrangement, the wooden rods are made reversible, and when they are pushed, so as to allow of the hooks T entering the holes H or S, and the rings C', or caps C are slipped, so as to engage under the hook T, the rods are made perfectly fast to the hook.

Claim.

The end-caps C, or rings C', slipping freely over the ends of the slotted rod A, and in combination with the hooks T, all constructed as shown and described, and for the purpose set forth.

H. UHRY. [L. S.]
